BUILDING CONSTRUCTION

Walter W. Macfarren, Los Angeles, Calif.

Application July 25, 1936, Serial No. 92,575

15 Claims. (Cl. 108—1)

My invention relates to building construction and more particularly to roofs, and is particularly well adapted for dwelling houses, bungalows, and other small buildings. Certain features of the construction however, are also adapted for use in large mill and manufacturing buildings, as will appear later.

In the drawings:

Fig. 1 is a skeleton plan of a rectangular roof frame according to my invention.

Fig. 2 is an elevation of the same, including the outside supporting, or wall columns.

Fig. 3 is a floor plan of a circular bungalow.

Fig. 4 is a floor plan of an elliptical bungalow.

Fig. 5 a diagrammatic elevation of a mill building.

Fig. 6 is a diagram of some catenary curves.

Fig. 7 is a diagrammatic cross section on the line 1—1 of Fig. 1.

Fig. 8 is an enlarged cross section through the outside wall of any figure.

Fig. 9 is an elevation of a portion of a corner outside wall column.

Fig. 10 is a cross section of a latticed welded floor beam.

Fig. 11 is a horizontal cross section of a corner outside wall column.

Fig. 12 is a horizontal cross section of a standard outside wall column.

Fig. 13 is a horizontal cross section of an inside wall column.

Fig. 14 is an elevation of the circular bungalow of Fig. 3.

Fig. 15 is a diagrammatic side elevation of a mill building.

Fig. 16 is a diagrammatic end elevation of the same.

If the house is to have a cellar, the same may be constructed in any suitable way. If not, the preferred construction is a concrete foundation wall and a concrete floor slab, both to be suitably reinforced and tied together. On top of the walls there is laid a steel bar or channel 1, secured to the walls by suitable foundation bolts (not shown).

Referring to Fig. 8, the base channel 1 is laid back up, and may be levelled and grouted underneath. On top of the channel 1 there are spaced wall columns 3 which may be secured to the channel 1 by foot bolts 4, which may have their heads spot welded to the underside of the channel.

When the concrete foundation has set, the base channels 1 may be set in place, levelled, and bolted down. Then, starting at any desired point, a wall column 3 may be set up and bolted to the

base channel 1. Then a wall slab 15 may be set up with one edge in the groove 16 of the column just set. Then a second column and a second slab may be set up, and so on until the whole outside wall is erected.

The top plate or truss 17 may then be set on the columns. This truss forms the eave of the roof, and extends entirely around the building, and holds the upper ends of the wall columns 3 in line. It consists of an outside member 18 which 10 I prefer to form of steel pipe of suitable size, an inner member 19 which rests on the column top channels 6, and for which a rolled angle is a convenient section, and a number of flat steel lattice bars 20 arranged to brace the members 15 18 and 19 together. The member 18 is welded to the outer ends of the various channels 6, and the member 19 is welded to their inner ends to form a truss.

The members 18 and 19 can be made in convenient lengths and welded end to end. If the truss 17 is fabricated in the shop it can be made in about 10 sections for the floor plans of Figs. 1 to 4, and if made in the field it can be made of any convenient lengths of material.

When the truss 17 is welded to the tops of all the wall columns 3, the bases of these columns can then be welded to the base channel 1. At this point we have a rigid steel structure to the eaves, and with the wall slabs 15 loosely in place.

In the design shown in Figs. 2 and 7 the eight central columns 26 carry practically the entire weight of the roof if the same is formed by a preferred method to be described later, and these columns and their foundations may be designed accordingly. To show the flexibility of the system I have shown in Figs. 3 and 4 other floor plans using the same outer walls and wall columns as shown in Fig. 2.

One of the main features of the present invention is the use of a roof built on the contour of a catenary curve.

According to the books "the catenary is the curve assumed by a perfectly flexible cord when its ends are fastened at two points, the weight of a unit length of the cord being constant"—i. e. uniform.

Fig. 6 shows three separate catenary curves (approximated by circular arcs) all assumed to 50 be supported from the common points A and B. The upper curve A C'' B is shallow and similar to the curve used in suspension bridges. The lower curve A C' B is a deep one similar to that used for suspended coal bunkers. The in- 55

termediate curve A C D B is one suitable for the roofs of small buildings.

It will be noted that in any of these curves, the stresses at the points C, C', or C'' are horizontal. In the curve A C D B, if a support be placed at the point C, and one at the point D, the portions A C and D B may be eliminated, and only the portion C D used for the roof in hand. This portion of the curve is the one used for the 10 rafters shown in Fig. 7.

All the points of the catenary curve may be figured mathematically, including the stresses for assumed loads, but the formula is complex, and for all practical purposes there is an easier 15 method. Considering one side of Fig. 7, the roof has a rise of one half its span.

In Fig. 6 it will be evident that if the points C and D represent the position of the eave and ridge of a proposed roof to a full size scale, a 20 cord may be stretched over them tightly in a substantially straight line as shown dotted. If the tension of the cord is gradually reduced, the cord will assume a variety of curves, each one of them being a true catenary, until a curve such 25 as C E D is reached. However curves much below the curve C D are not suitable for drainage. The desired curve to please the eye may be thus selected for small roofs in a few minutes.

Now it is also necessary to know the stress in 30 the cord in order to design the rafters or trusses. This may all be calculated by abstruse mathematical formulae but here again a simple method is available. In order to obtain the tension in any given catenary, a chain of known 35 weight per foot may be stretched to the desired curve, and its tension measured by a spring balance or other means, from which the tension due to any uniform load may be easily calculated.

However the loads on a roof are not uniform. 40 The roof must be strong enough to support workmen during erection and for subsequent repairs. Concentrated snow loads may occur, and the usual wind loads must be provided for as in any other type of roof. In the roof of Fig. 45 7 the snow will probably lie deepest at the lower portion of the curve, and the wind pressure will be greatest at the upper portion of the curve.

In order to provide for these varying conditions I prefer to make use of a pair of catenary 50 tension members one above the other, and connected by bracing one to the other, thus forming a trussed rafter or small roof truss.

In Fig. 7 the upper catenary tension member 55 27 may pass over a ridge pole or pipe 30, and be welded at each of its ends to one of the pipes 18 on either side of the house, and also to the ridge pole 30. The lower catenary tension member 28 may also have its ends welded to the side pipes 18, and its middle portion supported by a 60 pair of ridge poles 31, and the three ridge poles 30 and 31 may be connected by welded lattice bars to form a triangular truss. This construction is merely illustrative of a variety of suitable details.

65 The lattice bars 29 may have their ends welded to each other and to the members 27 and 28. The assembly of the members 27, 28, and 29 will be much lighter for an equal span and equal loads than a beam, because the principal or 70 dead load stresses in the members 27 and 28 are normally pure tension, as compared to the flexural stresses in a beam.

Either the members 27 and 28 may be of equal section to divide the load, or the upper member 27 may be designed to carry the full 75

load, and the lower member 28 may be made only strong enough to avoid distortion of the upper member 27 from the catenary curve when the rafter is subjected to uneven loading. As long as the loading is uniform and the upper member 27 keeps its true catenary contour the stresses therein are purely tension.

To support the ridge poles 30 and 31, I provide a series of A frames 32 resting on the eight central columns 26 of Fig. 7, and on the end 10 outside wall columns 3 in line therewith, if the roof slopes only to the side walls.

If the roof slopes both to the ends and sides of the house, I provide additional corner ridge poles 34, 35, 36, and 37 as indicated in Fig. 1, 15 and which are supported at their outer ends by the pipes 18, and at their inner ends by one end of the ridge pole 30. Since this design is for a welded assembly, I prefer to use common steel pipe of suitable sizes for the members 18, 30, 31, 20 34, 35, 36, and 37, as affording easy connections for the flat bar members 27 and 28, and being easy to weld to each other.

In order that each rafter may have the catenary form, the members 34, 35, 36, and 37 must 25 be bent to a curve which will be the intersection of the side catenary roof slope and the end catenary roof slope, which may be duplicate or different curves, and each member 34, 35, 36, and 37 may be built as a truss similar to the members 30 27 and 28.

As the rafters in this case are of different lengths, the construction will naturally be more expensive, and it is for the builder to determine whether the enhanced appearance is worth the 35 additional expense, just as with a roof framed of wood.

It is also to be noted that if the full length rafters 40 of Fig. 1, are bent to a true catenary, the shorter rafters may not be a true catenary, 40 but they will be close to one, and this is of no particular importance, as these rafters are trussed, and carry a lesser load than the full length rafters.

The assembled rafters of Fig. 7 may be designated as a whole by the numeral 40, and may be spaced from two to four feet apart depending on the type of sheathing used, and various building codes in cities. As sheathing to span the spaces between the rafters 40, wood, metal, or various 50 composite materials may be used.

For this purpose I prefer steel as being both light and strong, and because of its stiffness corrugated steel is ideal for the purpose. Such sheets are specifically designed for roofing, to be 55 laid on spaced purlins with their corrugations running down the roof slope. When so placed and lapped they are rain proof. However, for the present invention, the sheets are placed with their corrugations running horizontally, or at right 60 angles to the rafters 40. In such position they span the spaces between the rafters 40 efficiently, and being flexible parallel to their corrugations, they may be readily bent to the roof curve.

The sheets 38, so laid may be bolted, clipped, 65 or spot welded to the top rafter member 27. Above the sheets 38 I prefer to use a sheet copper cover 39, which may be fastened to the sheets 38 by small rivets. The combination of the steel corrugated sheathing and the sheet copper cover 70 gives a roof which is light, strong, water, wind, and fire proof, very durable, and of good appearance.

It is obvious however that practically any usual type of roofing materials may be employed; as 75

shingles, tile, slate, or various composition roofings. Wood shingles and the various tarred compositions are not sufficiently fire resistant, and slate or tile cause needless weight at a point where it does the most damage during an earthquake.

At 14 I show braces from the top of the outside walls to a central point of certain of the rafters 40. All these braces may be of flat steel bars or light angles with welded connections, and may be applied wherever needed almost as easily as a wooden brace may be cut and nailed.

The whole of the house may be provided with a ceiling at the level of the eaves, or certain rooms may be ceiled at the rafters 40. For the first case I prefer to use a suspended ceiling constructed as follows:

The angle 19 extends entirely around the house. The interior partitions may be built to an equal height and capped with a flat bar welded to the tops of the interior columns or studs. Upon these members and welded thereto, there may be placed a series of small flat bars 43, say $\frac{1}{8}'' \times 1''$ in section or even smaller, and spaced about two feet apart. Instead of flat bars, the members 43 may be small angles or channels, or the upper and lower members 43 may be any desired combination of flat bars, angles, or channels.

In the design of Fig. 1 these bars 43 should be set diagonally, or at an angle of 45 degrees with the outer walls, and all the bars should be welded to each other at their various intersections, thus forming a net or mesh similar to wire netting. To support these bars between the partitions I provide vertical ties 44 of flat steel, say $\frac{1}{8}'' \times \frac{1}{2}''$ in section, the upper ends of these ties being welded to the lower member 28 of the rafters 40, and their lower ends being welded to the upper sides of the ceiling bars 43. There may be a tie 44 at each intersection of the bars 43, and the ties may be inclined to meet the rafters 40 where necessary.

If a plastered ceiling is desired, metal lath may be wired, clipped, or welded to the bars 43 to receive the plaster. I prefer however to use some form of wall board or asbestos sheeting, which may be fastened directly to the under sides of the bars 43.

In certain cases it may be desired, for architectural effect, to place the ceiling just under the rafters 40.

It will be noted that since the tensile stresses in the catenary rafters are practically horizontal at the eaves, substantially the whole weight of the roof of Figs. 1 and 7 is carried by the central inside wall columns 26, which with their foundations must be designed accordingly.

The rectangular houses of Figs. 1, 2, 3, and 4 have 36 panels of 4 ft. each, or a wall periphery of 144 lineal feet and the enclosed gross area with a wall 6" thick is 27.5 x 43.5 or 1196 sq. ft.

The elliptical house of Fig. 3 may also have 36 panels of 4 ft. and the same wall periphery of 144 ft., but the gross enclosed area here is approximately 1560 sq. ft. It may be noted in passing, that it is not necessary to use a true ellipse, as a close approximation may be obtained by the use of four connected circular arcs, which are easier to lay out.

The circular house of Fig. 6 may also have 36 panels of 4 ft. and a wall periphery of 144 ft., but here the gross enclosed area is 1626 sq. ft. with 6" walls, or a gain of 430 sq. ft. in usable area with the same expense for the enclosing wall. This is a gain of over 36%.

While the rooms of Figs. 3 and 4 are unconven-

tional in shape, the plans seem to applicant to show equal utility and convenience, and a distinct improvement in architectural effect, both inside and outside, over the more conventional plan of Fig. 1. In Figures 3 and 4, the curved outside walls will cost little if any more than the usual straight walls, since the wall slabs may be cast in curved molds almost as cheaply as in flat ones.

In both these houses the rafters 40 may be duplicates of those used for the rectangular houses, but the curvature of the members 18 and 19 will add some expense, and a certain loss of efficiency will occur in the rafters because they are not parallel. The corrugated sheathing 38, and the copper covering 39 will also be cut to some waste of material.

Let us now pass from the details of bungalows to a wider consideration of one of the principal features of this invention, viz. the catenary roof. The simplest form of catenary roof is a metal sheet suspended by two of its ends or edges, to hang in a catenary curve, and combined with similar sheets to cover a desired area. Such a construction is indicated diagrammatically in Figs. 15 and 16, in which such sheets 60 are supported between adjacent roof trusses 59, forming a flat shallow trough between the trusses which should be sloped toward the outer walls of the building for drainage. In sites where there were no winds, such an arrangement might be suitable, without any bracing for the roof sheets 60. But such locations are rare.

Now if at intervals of three to five feet, light flat bars 61 are suspended under the sheets 60 and in parallel relation thereto, such bars may be connected directly to the sheets 60 by welded lattice bars 62, to stiffen the sheets.

In this way a standard mill building construction could be used with bays of say 20 feet, and using standard or usual columns and roof trusses; the usual purlins and corrugated sheet roofing being eliminated, and replaced by the suspended catenary roof sheets 60, and the bracing members 61 and 62.

A roof of this kind would certainly be lighter than the usual construction of purlins and corrugated sheets, as the purlins are necessarily strong enough to resist flexure, as are also the corrugated sheets. This is the prime reason for corrugating them. On the other hand the catenary sheets 60 and the brace bars 61 are in pure tension when under uniform loads.

A further application of this principle for buildings of wide span is indicated in Fig. 17, which will in a sense eliminate roof trusses.

In this case the usual steel building columns 63 could be used, having a continuous beam or truss 64 running along their tops. This member would take both vertical and horizontal loads. Between each pair of opposite columns 63, a horizontal compression member 65 is placed, to span across the building.

From the upper surfaces of the opposite trusses 64, the roof sheets 66 may be stretched, and between the roof sheets 66 and each of the horizontal compression members 65, spaced vertical ties 67 may be placed. These may either be threaded rods with nuts, or welded ties as previously described.

This construction forms a truss in which the top member is in tension and the bottom member in compression, being the exact reverse of usual practice. In this case also, the weight of the members 65 and 67 is supported by the roof sheets 66, and the tension of the sheets 66 is balanced.

by stresses in the trusses 64, and compression in the members 65.

Also, in this case the curve of the roof sheets 66 would not be a true catenary, but could be made to approach this curve to any desired degree by closer spacing of the tie bars 67, or by branching them as indicated at 68. Such a roof being fairly flat, would not be affected by ordinary winds, and snow loads would be fairly uniform. It is thought that roof spans of 100 feet or more may be practical with this system, and that proper calculations will show a considerable economy in material.

In roofs of the type shown in Figs. 5, 15 and 16, the most practicable material for the roof sheets 60 and 66 is steel. The sheets could have adjacent edges lapped and welded. They should be of copper alloy steel, or other non-corrosive metal. For the cover sheets 39 of Fig. 7 copper sheets are the best, but very likely a copper alloy or brass sheet would be good enough and cheaper.

To summarize, a roof employing the catenary curve, with the sustaining members in pure tension under uniformly distributed loads, may fall under any one of the following five general classes:

1. The roof may consist of a single sheet of metal or other material, stretched in a catenary curve, and being self supporting under its own tension.

2. The roof may consist of a metal sheet as above, and having attached spaced catenary braces to take eccentric or non-uniform loads.

3. Instead of the covering sheet being self-supporting as in 1 and 2, the same may be supported on catenary rafters or tension members, with interposed sheathing, and such rafters may either have sufficient stiffness in themselves, or be braced or trussed, to carry non-uniform loads.

4. The roof covering sheet may be a composite member such as a concrete slab with steel reinforcing bars, the slab being laid in a catenary curve with the reinforcing bars adapted to take the tensile stresses produced by the weight of the slab. Various other forms of composite roof covering may be used, such as asbestos sheets containing steel wire mesh. The essential requirement is that the roof covering be wind and water tight, and that it be laid in a catenary curve or one substantially similar thereto, and that the covering sheet, or its supports possess sufficient strength for safety.

5. The roof of a large building may be subdivided into sections, of which each section is a separate unit partaking of the characteristics of some of the above classifications, or combined with older forms.

Having now set forth my invention in various preferred forms, and in such detail that those skilled in the various related arts may apply it, I claim as my invention:

1. In a building structure, supporting members such as columns or walls, a roof comprising a sheet of material adapted to resist tensile stresses, the said sheet being suspended in the form of a catenary curve, and continuous bracing means extending from one sheet support to the other, to prevent distortion from the said catenary curve.

2. In a building structure, supporting members such as columns or walls, roof trusses supported thereby, a roof comprising a sheet of material adapted to resist tensile stresses, the said sheet being suspended in sections between adjacent roof trusses in the form of a catenary curve,

and a continuous lattice for bracing the said roof sheet against distortion from the said curve.

3. In a building structure, two lines of parallel building columns, a truss extending along the tops of the said columns and adapted to resist both horizontal and vertical stresses, roof sheets adapted to resist tensile stresses stretched across the building and secured to the said trusses, compression members extending across the building below the said roof sheets and between opposite building columns, and tie rods connecting the said roof sheets and the said compression members to support the latter.

4. In a building structure, supporting members such as columns or walls, rafters spanning the said supports, each of the said rafters comprising a pair of tension members spaced apart vertically, and curved to the contour of a catenary, bracing members connecting the said catenary tension members to obtain rigidity, and a roof covering supported directly on the said rafters.

5. A steel frame for a building structure, comprising in combination outside wall columns, a ridge pole, catenary rafters supported by the above two elements, the said rafters each being composed of two flat bars in substantially parallel relation and connected by lattice bars, and corrugated steel sheathing secured to the said rafters with its corrugations set horizontally to support a weatherproof covering.

6. A steel frame for a building structure, comprising in combination outside wall columns set in a continuous curve, inside wall columns in supporting relation to the roof, a continuous truss supported by the said outside wall columns, and adapted to resist both horizontal and vertical stresses, and a roof carried by said inside wall columns and by said truss and which in vertical section has the contour of a catenary curve, and in which the supporting members thereof are in pure tension under uniform loads due to their catenary contour.

7. In a building structure, roof supporting members, transverse roof trusses supported thereby, a roof sloping both ways from a ridge extending lengthwise of the structure toward the sides thereof, the said roof comprising sheet material adapted to resist tensile stresses, and hung in sections secured to adjacent roof trusses, each section being hung in the form of a catenary curve extending from one roof truss to the next, the upper surfaces of the said roof sections forming wide shallow troughs extending across one half the width of the structure and the said sheet material being curved in one direction only.

8. In a building structure, supporting members, a horizontal truss or plate extending along the tops of certain of the said members, a ridge pole supported by certain of said members, catenary rafters spanning from the said ridge pole to the said plate, a roof covering over the said rafters and supported thereby, a series of criss-cross bracing bars extending horizontally to cover the area enclosed by the said plate, and secured to the said plate to brace it against the pull of the catenary rafters, and tie bars connecting the said rafters and the said cross bars to support the latter.

9. A fabricated steel rafter for building structures, comprising in combination an upper member in the form of a flat bar, and which is bent to form a catenary curve, a lower member also in the form of a flat bar, and bent to a catenary curve substantially parallel to the curve of the upper member, and flat lattice bars connecting

the said upper and lower members to obtain rigidity.

10. A fabricated steel rafter for building structures, comprising in combination an upper member in the form of a flat bar, and which is bent to form a catenary curve, a lower member also in the form of a flat bar, and bent to a catenary curve substantially parallel to the curve of the upper member, and flat lattice bars having their ends welded respectively to the said upper and lower members, and with their respective edges adjacent to the edges of the said upper and lower members.

11. A fabricated steel rafter for building structures, comprising in combination an upper member in the form of a flat bar, and which is bent to form a catenary curve, a lower member also in the form of a flat bar, the same being bent to a catenary curve substantially parallel with the curve of the upper member, and flat lattice bars connecting the said upper and lower members to form a rigid structure, the said upper member being proportioned to support all uniform loads, and the said lower member being proportioned to take such eccentric loads as may reasonably be expected to be placed on the roof.

12. A fabricated steel rafter for building structures, comprising a non-flexible bar having upper and lower flanges and a central portion connecting the said flanges, the same being bent to

a catenary curve, so that when it is suitably mounted on a building frame it may support uniform loads by a purely tensile stress, and may support non-uniform loads by its inherent stiffness.

13. In a roof structure, a ridge pole comprising three parallel members set on the corners of a triangle, lattice bars connecting each of the said members with two of the others, supports for the said ridge pole, and catenary rafters 10 extending from the said ridge pole to an eave of the roof.

14. In a building structure, roof supporting members, straight parallel rafters supported thereby, and being sloped for drainage, and a 15 roof covering comprising sheet material adapted to resist tensile stresses, and hung on the said rafters in parallel catenary shaped troughs extending from rafter to rafter, to cover the space below the rafters.

15. In a building structure, roof supporting members, a ridge pole, straight parallel rafters extending from said ridge pole to an eave of the roof, and being sloped for drainage, and a roof covering comprising sheet material adapted 25 to resist tensile stresses, and hung on the said rafters in parallel catenary shaped troughs extending from rafter to rafter, to cover the space below the rafters.

WALTER W. MACFARREN. 30
